UNITED STATES PATENT OFFICE.

ARCHIBALD L. WALLACE, OF NEW YORK, N. Y.

WRENCH.

Application filed November 21, 1922. Serial No. 602,381.

To all whom it may concern:

Be it known that I, ARCHIBALD L. WALLACE, a subject of the King of Great Britain, residing at the borough of Manhattan, in the city, county, and State of New York, have invented certain new and useful Improvements in Wrenches, of which the following is a full, clear, and exact specification.

10 This invention relates to wrenches and my improvement is directed to that class of wrench which consists of a handle or lever portion and a chain or other flexible member adapted to extend from the handle or lever, to wrap about the work object, and to engage at its free end with the handle or lever in effecting its grip upon the work object.

15 It is desirable that the flexible member, or a slack length thereof, shall be normally housed within the handle, which is made hollow or tubular for the purpose, and it is also desirable that the flexible member be capable of withdrawal from the hollow handle, for service, against the tension of 20 a spring which operates to retract it when released.

25 Also it is desirable that means be provided to lock the flexible member in a set position relatively to the handle with an extended length thereof engaged about a work object, in order that the work object may be gripped and turned when the wrench is moved in one direction, and released when the wrench is moved in the 30 other direction.

35 Therefore my invention consists in providing a hollow wrench handle with a stop device fixed therein at a point intermediate its length, a plunger movable relatively to said stop, the plunger engaging the flexible member at one end and a spring which lies between the stop device and the plunger to hold the flexible member normally 40 retracted. Also my invention includes the provision of locking means, mounted on the handle, and operable through the wall thereof to lock the plunger in any adjusted position of the flexible member when grip- 45 pingly wrapped about a work object.

50 Also, in my improvement the flexible member is provided with terminal engaging means in the form of parallel hooks, spaced apart for the passage of the flexible member and adapted to co-act with terminal, parallel lugs extended from the handle, the

engaging surfaces of the hooks and lugs having complementary curvatures.

Other features and advantages of my invention will hereinafter appear. 60

In the drawing:

Figure 1 is a longitudinal, side sectional view of my improved wrench.

Fig. 2 is a top plan view thereof, and Fig. 3 is a section on the line 3-3 of 65

Fig. 1.

In said views let 1 indicate a hollow handle constituting the lever or stock portion of the wrench. This handle may consist of a section of metallic tubing, and 70 is here shown as provided with a stopper 2 screwed into its rear end, as closure means therefor.

At its forward end the tubular handle is flattened to provide the relatively straight 75 sides 3, 3, which terminate in the lugs 4, 4, each having a like, rounded perimeter 5, and a rearwardly inclined edge 6. Also at the forward end of the tubular handle its upper wall, which is cut away to leave a 80 clearance between said end and the lugs 4, 4, is depressed as at 7, the depression resulting in the formation of a lip-like bearing for the flexible member in its movement in and out of the handle. 85

The flexible member is here represented as a chain 8 composed of pivotal links. One end of the chain is connected, as by pivot 9, with one end of a bar 10, to whose opposite end there is connected a disk or cap 11, 90 as by screw 12, this disk or cap being of such circular dimension as to fit slidably within the handle.

Located within the handle, at a point 95 therein intermediate its length, is a block 13, said block being secured to the handle in a set position, as by a screw 14. The block 13, which is recessed at 15 to slidably receive the bar 10, serves as a forward stop for a helical spring 16, that surrounds bar 10, and is confined between block 13 and cap 11. 100

The spring 16 is normally extended to hold the bar 10 and chain 8 retracted within the handle, but upon drawing the chain outwardly thereby the spring becomes contracted between block 13 and cap 11, storing energy in this operation for the subsequent retraction of the bar and chain. Entered 105 within a slot 17 provided in the upper portion of the handle is a shoe 18, whose inner surface is serrated to engage in serrations 110

19 formed on the opposed surface of bar 10, for the purpose of locking the bar 10 in a set position lengthwise relatively to the handle.

5 The shoe 18 is carried by a flat spring 20, to which it is secured as by a screw 21 that centrally unites these members. The spring 20 fits at its opposite ends respectively in nicks or slits 22, 22 provided in a bridge 10 member 23, that spans the slot 17 and is secured, as by screws 24, 24 to the handle.

Hence it is by the exercise of pressure, applied to spring 20, that the shoe may be caused to engage the bar 10. The shoe is 15 guided in its movement by means of lugs 25, 25 extended from block 13.

Mounted on bridge member 23, as by a transverse pivot 26 is a yoke-like thumb piece 27, which has an inner, terminal cam 20 surface 28, adapted, when the thumb piece is rocked in one direction, to depress spring 20, thereby moving shoe 17 inwardly in the performance of its bar locking operation. But, when the thumb piece is rocked in the 25 other direction thereby spring 20 is released by the cam, and in consequence the shoe is withdrawn from its engagement with the bar.

The outer end of chain 8 has a terminal 30 member composed of the block portion 29, recessed to receive the end link of the chain, to which it is pivotally connected, and side bars 30, 30, which are spaced apart, in parallelism, and continue into the hook portions 31, 31. The spacing between these hook portions is sufficient to freely receive the chain as it is wrapped about the work object, because in the operation of the device, when for example a pipe α is to be 35 turned, the chain is drawn out of the handle, passed around the pipe, and its hooks 31, 31 respectively, engaged with the lugs 4, 4, leaving a slight clearance between the block portion 29 and incline 6, as in Fig. 1, with 40 the hooks straddling the chain at the point of its emergence past the lugs 4, 4.

By this means the chain is enabled to 50 form a complete encircling ring about the pipe, because the rear surfaces of the hooks lie against the pipe, and the chain portion which lies between the hooks is thereby enabled to also engage the pipe. With the chain thus wrapped about the pipe by means of a sufficient length thereof extended 55 against the spring tension, the chain must then be locked, by engaging shoe 18 with bar 10.

It then follows that by moving the handle 60 downwardly, any slight slack therein is absorbed in the clearance between block 29 and incline 6, whereupon a powerful grip of the chain upon the pipe is attained, and in moving the handle upwardly this grip is released.

65 Variations within the spirit and scope of

my invention are equally comprehended by the foregoing disclosure.

I claim:—

1. The combination, in a wrench having a hollow handle, and a flexible gripping member partly containable therein, of a plunger engaged with the inner end of the flexible member, a spring to extensibly retain the flexible member partly within the handle, and manually operable means to lock the plunger to the handle and thereby hold the flexible member in an extended operative position. 70

2. The combination, in a wrench having a hollow handle, and a flexible gripping member partly containable therein, of a bar having a head at one end and means of engagement with the flexible member at its other end, said bar movable longitudinally within said handle, fixed stop means within the handle, and a spring lying between the fixed stop means and bar head to extensibly retain the flexible member partly within the handle. 80

3. The combination, in a wrench having a hollow handle, of a block, having guide means, fixed within said handle, a bar slideable through the guide means, a flexible member engaged with said bar and extended beyond the handle, and a spring operable between the block and bar to extensibly retain the flexible member partly within the handle. 90

4. The combination, in a wrench having a hollow handle, of a block, having guide means, fixed within said handle, a bar slideable through the guide means, a flexible member engaged with said bar and extended beyond the handle, a spring operable between the block and bar to extensibly retain the flexible member partly within the handle, and means, operable through the side of the handle, to lock the bar and thereby hold the flexible member in an extended, operative position. 100

5. The combination, in a wrench having a hollow handle, of a bar longitudinally slideable therein, said bar engaging a flexible member which extends out beyond the handle, spring means co-acting with the bar to extensibly hold the flexible member partly within the handle, said handle provided with a slot in its side, a shoe movable in said slot to and from said bar, spring means to hold said shoe normally disengaged from said bar, and manually operable means to press the shoe into locking engagement with the bar. 115

6. The combination, in a wrench having a hollow handle, and a flexible gripping member partly containable therein, the handle having a slot therein, of a plunger engaged with the inner end of the flexible member, a spring to extensibly retain the flexible member partly within the handle, 125

a shoe movable through the slot, a bridge piece covering the slot, a spring engaged with said bridge piece and holding the shoe normally retracted, and a manually operable cam, pivoted to the bridge piece, to press the shoe into locking engagement with the plunger.

7. The combination, in a wrench having a handle and a flexible gripping member extensible therefrom, of parallel, spaced lugs, with curved terminal edges extended from the handle, said lugs spaced apart for

the passage between them of the flexible member, and parallel, terminal hooks for the flexible member, also spaced apart to 15 straddle the flexible member, the hooks having seating curvatures complementary to the curved edges of the lugs, to co-act therewith in enabling the flexible member to completely enwrap a work object.

Signed at the borough of Manhattan, in the city, county and State of New York, this 20th day of November, 1922.

ARCHIBALD L. WALLACE.
